WALL CONSTRUCTION

Joseph W. Schneller, Eggertsville, David A. Harris, Kenmore, and Rodney G. Buergin, Tonawanda, N.Y., assignors to National Gypsum Company, Buffalo, N.Y., a corporation of Delaware

Filed Aug. 24, 1960, Ser. No. 51,620

5 Claims. (Cl. 50—146)

This invention relates to walls for building structures and particularly to a novel means for supporting vertical building walls wherein said means consist solely of folded, paper-enclosed, gypsum-core wallboards attached to a structure at the bottom and top ends of the folded boards.

The present invention relates primarily to non-load-bearing, hollow, internal partition walls for building structures, however, it is not intended that the invention be definitely so limited. Partition walls may be divided into two general classifications, solid partitions normally having no form of studs, and hollow partitions, normally including a plurality of separate studs at spaced positions therealong to which the material of the two opposed partition faces are attached.

It is an object of the present invention to provide a hollow partition having gypsum wallboard wherein the gypsum wallboard includes portions thereof providing the function of studs.

It is a further object thereof to provide an improved hollow partition of markedly simplified erection.

It is a still further object of the invention to provide a novel hollow partition at substantially reduced costs of materials as well as labor.

These and other objects and advantages of the invention will be more readily apparent when considered in relation to the preferred embodiment as set forth in the specification and shown in the drawings in which:

FIG. 1 is a front elevation of a section of plastered partition wall constructed in accordance with the invention, portions being shown broken away.

FIG. 2 is a sectional view taken on line 2—2 of FIG. 1.

FIG. 3 is an enlarged sectional view taken on line 3—3 of FIG. 1.

FIG. 4 is a front elevational of a drywall partition wall partially constructed in accordance with the invention.

FIG. 5 is a sectional view taken on line 5—5 of FIG. 4.

FIG. 6 is an end sectional view of the gypsum board framing element of FIG. 1 in collapsed form for storage and shipment.

FIG. 7 is an isometric view of an end corner section of the framing elements of FIGS. 1 and 4.

FIG. 8 is an isometric view of the metal corner clip of FIG. 7.

FIG. 9 is an isometric view of a modified corner clip formed of wire.

FIG. 10 is an end sectional view at a ceiling juncture of the framing elements of FIGS. 1 and 4.

FIG. 11 is an end sectional view at a floor juncture of the partition of FIG. 1.

FIG. 12 is an isometric view of one of the floor runners of FIG. 11.

FIG. 13 is a sectional plan view of a corner of partition constructed in accordance with the invention.

FIG. 14 is a front elevational of a doorway in a partition wall constructed in accordance with the invention, portions being shown broken away.

FIG. 15 is a sectional plan view of the door buck section taken on line 15—15 of FIG. 14.

FIG. 16 is an isometric view of a modified section of a partition framing element for use around electrical conduits.

FIG. 17 is a sectional plan view of a modified joint

2

section of partition framing elements in accordance with the invention.

FIG. 18 is a sectional plan view of a further modified joint section of partition framing elements in accordance with the invention.

Referring now to FIGS. 1 to 3, there is shown a building floor 10 and ceiling 12 with a section of plastered, hollow partition wall 14 extending therebetween. Wall 14 consists of a plurality of vertically extending folded gypsum board hollow boxes 16 centrally aligned and abutted end to end along the extent of wall 14, providing the sole framing means of the wall 14, and having coated on both of the opposed faces of the boxes 16 a normal set gypsum plaster wall surface 18. Narrow expanded metal lath strips 20 are affixed, as by stapling, over the joints between boxes 16 for firm retention of the plaster surface 18 at the joints.

The vertically extending gypsum board boxes 16 are each made from a single paper covered gypsum board, 20 with the commonly known set gypsum core 22 enclosed in paper liners 24, 26 on the two opposed faces thereof. The boxes are formed by partially severing the gypsum boards along three spaced parallel lines or cuts 28, leaving the inner paper liner 24 unsevered to function as a 25 hinge along each cut, in folding the gypsum board into elongate hollow boxes. The cuts 28 are spaced to form alternately narrow stud sections 30 and relatively wider facing sections 32, the width of the stud sections 30 being predetermined in accordance with the thickness 30 of the partition desired, as will be fully discussed below.

In the plastered wall 14, with boxes 16 disposed in abutting relation continuously therealong, stud sections 30 of two adjacent boxes 16 are disposed flush, one with the other, having the lateral direction of the stud sections 35 30 perpendicular to the general plane of the wall 14. Stud section reinforcing nails 33, preferably four 10-penny box nails at least every 24 inches of vertical extent of abutting stud sections 30, are toe-nailed through the four adjoining facing sections 32 into the combined two 40 abutting stud sections 30, as shown in FIGS. 1 and 3.

The invention is also shown embodied in a dry-wall type partition wall 34, in FIGS. 4 and 5, erected vertically between floor 10 and ceiling 12. Wall 34 consists of a plurality of vertically extending folded gypsum board 45 hollow boxes 16, completely similar in structure to the boxes 16 of FIGS. 1 to 3. In the wall 34, the boxes 16 are centrally aligned along the extent of wall 34, spaced apart one from another a distance substantially equal to the width of the facing sections 32 of the boxes, 50 whereby the narrow stud sections 30 are disposed in equally spaced relation along the extent of wall 34. Standard paper covered, gypsum core gypsum wallboards 36 are adhesively laminated to the two opposite outwardly 55 directed faces of the boxes 16, with the end joints of wallboards meeting on alternate boxes, as shown in FIG. 4. All joints of wallboards 36 may be treated in the usual manner, not shown, with wallboard joint tape and joint cement to conceal the joints, as is well known in the art.

In the preferred embodiments of the invention shown, the unsevered paper liner 24, of the boxes 16, is reinforced by 140 pounds per 3,000 square foot weight, pre-gummed, kraft paper reinforcing strips 38 adhesively laminated along areas whereat the board has cuts 28. 60 A strip 38 is also adhesively secured to the liner at the two side edges 40 extending across the joint thereof, affixing the two side edges in adjoining relation. In the present embodiment two strips 38 per box 16, each wider than the stud section 30, each provide reinforcement at the two 65 hinges of each respective stud section 30. There is thus formed a single, unitary, closed construction of the box 70

16, which is readily collapsible for compactness in shipping, as shown in FIG. 6, when not fixed and stabilized as described below, in the open box form of FIGS. 2 and 5.

As seen in FIGS. 3, 6 and 7, the facing section 32 which includes a side edge 40, is slightly wider than the other facing section 32 of each respective box, preferably by a difference equal to about $\frac{1}{4}$ of the thickness of the stud section against which the wider facing section abuts in the opened, rectangular box form, providing an overlapping of the wider facing section onto the edge of the stud section, for better transfer of loads or stresses from each one such section to the other.

The above-described folded gypsum board hollow box 16 will accordingly be seen to be equally well described as an elongate open-ended foldable unitary wall supporting core structure 16 consisting of four parallel, rectangular, elongate sections of flat gypsum board 30, 32, all adjoined substantially solely by the common inner face paper liner 24 and, at one juncture, solely by the elongate flexible sheet material or reinforcing strips 38. In particular, it will be seen that the separate sections 30, 32, adjoined along their respective elongate side edges by the common inner face paper liner 24, are not in any way adjoined by the gypsum core 22 or outer liner 26, however, the junction of sections by the inner face paper liner is preferably reinforced by reinforcing strips 38, adhesively secured to the exposed face of the inner face paper liner 24.

In FIG. 7 there is seen an end corner of a gypsum board box 16 with two formed sheet metal corner clips 42, slidably affixed onto adjoining stud and facing sections 30, 32, one at each corner in FIG. 7. Clip 42, seen alone in FIG. 8, includes two perpendicularly disposed board-edge-receiving pockets 44, 44. The bottom wall 46 of each pocket has a pointed knock-out 48 bent into the pocket for penetration into the gypsum core 22 of the box. An alternative, but generally similar, wire clip 50 is shown in FIG. 9, also including two perpendicularly disposed board edge receiving pockets 52, 52. The use of clips may be completely avoided by the insertion and affixing, as by nails, of a suitable small block of wood, not shown, within the opening of the box, at the end.

In the preferred embodiment, a clip 42 is attached to each corner of the box 16, at both ends of the box 16, requiring 8 clips per box. The clips 42 are attached immediately prior to erection, on a job site, and have been found to provide completely sufficient stability to the box structure during the immediately subsequent application of either the plaster surface 18 or the wallboards 36. On completion of the partition construction, the plaster surface 18, or the wallboards 36, provide complete stability to the novel folded gypsum board boxes 16 within the partition, providing a cooperative relation therebetween wherein the continuous wall facing structure prevents movement of the facing sections 32, by otherwise possible slight folding actions at cuts 28.

In FIG. 10 a vertical cross section of the ceiling junction of wall 14, without the plaster surface, shows the preferred manner of affixing in a building the top edges of the box 16. An elongate, L-shaped, metal ceiling runner 54 is affixed to the ceiling 12, as by nails 56, and the top end of open formed box 16 is affixed against the downwardly extending flange of the runner 54 with common fence staples 58. Elongate strips of cornerite 60, which are elongate strips of expanded metal formed into an L-shape, are attached to the ceiling and box along the top edge opposite the runner 54, when a plaster surface 18 is to be applied to the box 16. In a drywall application, such as FIG. 4, the one runner 54 is used in mounting the boxes 16, and on completion of the wall, moulding strips, not shown, may be applied to both sides of the wall at the ceilings.

FIG. 11 shows a vertical cross section of wall 14, at the junction with floor 10, with metal base 62 on one

side and rubber base cove 64 on the opposite side. The metal base 62 is attached by means of known base attaching clips 66, as in U.S. Patent 2,358,277 of J. J. Manofsky. The box 10 is disposed on and retained in position relative to the floor 10, by a pair of oppositely disposed elongate base runners 68, which are affixed to floor 10 by nails 56 prior to mounting of boxes 16. A short extent of runner 68, seen clearly in FIG. 12, includes a flat bottom 70, with nail holes 72, to be disposed under boxes 16, a vertical central flange 74 extending upwardly from bottom 70, for engaging the bottom edge of the outwardly directed faces of boxes 16, and an outwardly directed top flange 76 to provide a ledge for wallboard 36 in drywall construction, or a screed for applying plaster in a plastered wall construction. FIG. 13 is a sectional plan view of a partition corner constructed in accordance with the invention, wherein two perpendicularly disposed boxes 16 are affixed together with a stud section 30 of one box abutting a facing section 32 of a second box along the edge thereof.

An elongate, L-shaped, runner 54, as used for ceiling attachment, is attached by staples 58, one flange to one box and the other flange to the other box. A metal lath strip 20 is attached over the one flat joint formed, and elongate corner bead 78, in any commonly available form, is attached as by stapling over and along the outside corner. A plaster surface 18 encases the boxes 16 throughout.

FIGS. 14 and 15 show the manner in which a standard metal door frame 80 is combined with the partition of the invention. Door frames 80, with two vertical sections 82 and an overhead section 84, all of the usual preformed outwardly opening channel form, with a channel opening equal in width to the thickness of boxes 16, are mounted between two spaced apart, room height boxes 16 whereat a doorway is desired. The boxes 16 extend partially into the vertical sections 82 of the door frame, and inwardly thereof the frame is fully grouted, as shown, with a plaster grout 86. Short sections of boxes 16 are then inserted into the overhead section 84 of the door frame 80, which may also be grouted.

FIGS. 16 and 17 show modified forms of the invention wherein a modified three-sided folded gypsum board box 90, either manufactured in such three sided form, or made by the removal of a side edge portion of a box 16. The three-sided box is fixed in an open-box form by affixing to the edges 92, 92 of the two facing sections 94, 94 a plurality of spaced apart formed sheet metal edge-spacing clips 96, FIG. 16. Alternatively, the edges 92 may be fixed in the proper spaced relation by disposing the edges overlapping about a stud section 30 of an adjacent box as in FIG. 17. Stud section reinforcing nails 33 are preferably toe-nailed into the box stud section 30.

The three-sided box 90 may be used, as a necessity, in combination with the four sided boxes 16, when fitting boxes around utilities, such as the electrical fittings 98 shown in FIG. 16. Alternatively, the three sided boxes may be used completely throughout a partition, in the form shown in FIG. 17. The three sided box structure, having substantially closed joints, is also particularly adapted for use as a substantially complete partition of itself without a further plaster or wallboard surfacing, but merely, by way of example, applying tape to the joints or a wallpaper to the entire surface.

A further modified form of the box 100 is shown in FIG. 18, wherein stud sections 102 are formed along the centerline of a single paper covered gypsum board 104 by the severing of the paper liner 106 on one side of the board at one edge 108 of the stud section 102 and the severing of the opposite paper liner 110 at the other edge 112 of the stud section, fracturing the core, also, along each edge 108, 112, whereby the unsevered paper, or hinge, at each respective edge is on an opposite side of the board 104. Reinforcing strips 38 are adhesively laminated over the unsevered paper at the two stud section

edges 108, 112. In erecting a partition with boards 104, the board is bent in the two opposite directions at the edges of the stud section 102, until the stud section is perpendicular to the two planes of the oppositely directed facing sections 114, and corner clips 42 are affixed to the board ends at the junctions of the facing sections 114 and stud section 102. The modified box 100 is provided by erecting the thus folded boards 104 in overlapping relation wherein in each stud section 102 of one board 104 has overlapped on one edge a facing section of an adjacent board 104, and overlapped on the other edge a facing section of another adjacent board 104 on the opposite side thereof, all as shown in FIG. 18. Reinforcing nails 33 extend through the facing sections 114 into the stud section 102. A plaster surface 18, and/or wallboard 36, are applied over the modified boxes 100.

Having completed a detailed disclosure of the preferred embodiments of our invention so that those skilled in the art may practice the same, we contemplate that variations may be made without departing from the essence 20 of the invention or the scope of the appended claims.

We claim:

1. An elongate open-ended foldable utility wall supporting core structure comprising four parallel, rectangular elongate sections of flat gypsum board, each said section having two parallel elongate side edges, paper liner bonded to the gypsum core on each of the two opposed faces of each section, forming on each section an inner face liner and an outer face liner, exposed gypsum core on both the elongate side edges of two sections and on at least one side edge of each of the other two sections, the said four sections being adjoined along the elongate side edges to form a unitary hollow tube foldable to an open rectangular cross section with said inner face paper liner on the four sections forming the inner surface of said tube, the side edges of said inner face paper liners of each section each adjoined to an adjacent section inner face paper liner side edge, the remaining two elongate side edges of said other two sections being adjacent one another and adjoined solely by an elongate flexible sheet material affixed to the edge portions of the respective inner face liners of said other two sections and spanning the junction therebetween, the said section side edges having exposed gypsum being adjoined to adjacent sections substantially solely by means of said inner face liner on said sections being a single continuous paper common to all said four sections and forming flexible joints therebetween, said gypsum core of each section having a substantially uniform thickness throughout the extent of each section to provide uniform rigidity and strength throughout each section and the maximum ability of each section to transfer stresses to and from adjacent sections, said core structure being foldable to a flat, compact form for shipment and to an open rectangular cross section tube form for erection as a partition wall core.

2. A wall supporting core structure as defined in claim 1, wherein reinforcing strips of flexible sheet material are adhesively laminated to said inner face liner at said flexible joints.

3. A wall structure comprising a plurality of horizontally aligned, vertically disposed, elongate, open-ended unitary hollow wall supporting core structures, disposed centrally along the extent of said wall structure, said hollow wall supporting core structures consisting of four parallel, rectangular, elongate sections of flat gypsum board, each having two parallel, elongate side edges, paper liner bonded to the gypsum core on each of the two opposed faces of each section forming on each section an inner face liner and an outer face liner, exposed gypsum

core on both the elongate side edges of two sections and on at least one side edge of each of the other two sections, the said four sections being adjoined along the elongate side edges to form a unitary hollow tube foldable to an open rectangular cross section with said inner face paper liner on the four sections forming the inner surface of said tube, the side edges of said inner face paper liners of each section each adjoined to an adjacent section inner face paper liner side edge, the remaining two elongate side edges of said other two sections being adjacent one another and adjoined solely by an elongate flexible sheet material affixed to the edge portions of the respective inner face liners of said other two sections and spanning the junction therebetween, the said section side edges having exposed gypsum being adjoined to adjacent sections substantially solely by means of said inner face liner on said sections being a single continuous paper common to all said four sections and forming flexible joints therebetween, said gypsum core of each section having a substantially uniform thickness throughout the extent of each section to provide uniform rigidity and strength throughout each section and the maximum ability of each section to transfer stresses to and from adjacent sections, said wall core structures being rigidly affixed at the bottom and top edges thereof to a building structure, said wall core structure being self-supporting intermediate of said bottom and top edges and providing the sole supporting means of said wall structure, and wall surface material disposed on the faces of said wall core structure and adjoining said plurality of wall supporting core structures into a unitary wall structure.

4. A wall structure as defined in claim 3, wherein said wall core structures are disposed in abutting relationship, one to another, substantially throughout the extent of said wall structure, and wherein said abutted wall core structures have a set gypsum plaster wall surface coated thereon, forming thereon a continuous, monolithic, finished wall surface.

5. A wall structure as defined in claim 3, wherein said wall core structures have exposed wall boards affixed to the said wall core structures, whereby said wall core structures form a supporting core of said wall structure, and said wall boards form a continuous finished wall surface enclosing said plurality of wall core structures.
